UNITED STATES PATENT OFFICE

2,448,020

DEVICE FOR HIDDEN EXPLOSIVE MINES

Richard C. Darnell, Champaign, Ill.

Application May 17, 1943, Serial No. 487,295

2 Claims. (Cl. 102—3)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to explosive mines of the type which are hidden from view, usually by being buried in the ground, and provided with means which will cause the mine to explode when an object comes within the range of its effectiveness. Detectors have been developed for seeking out or locating such hidden mines, so that they may be safely destroyed. Such mine detectors usually operate with electromagnetic waves and are implemented with an exploring loop which is traversed over the ground, a deflecting needle or the like indicating the presence of the hidden metallic body; electromagnetic detectors are effective to locate non-magnetic as well as magnetic mines provided they contain metal parts.

The object of this invention is to devise a means which will thwart and deter the electromagnetic detection of hidden mines by causing the explosion of the mine, and the destruction of the exploring party and the detector, when it comes within the electromagnetic field of the exploring loop of the detector. The invention is particularly designed for anti-tank mines the primer of which is fired when the large mass of the tank comes within its range of effectiveness, but will not be fired when the mine is approached by bodies or bodies containing no large mass of material. Hence anti-tank mines will not explode when approached by exploring parties or by the exploring loop of the detector or the detector box itself. The specific object of this invention is to devise a means for exploding an anti-tank mine or mines when approached, not only by a tank but by the exploring loop of a detector seeking to locate the mine. It is the purpose of the invention to sow a small number of such explosive devices among the standard anti-tank mines, so as to deter or discourage the attempts to locate the hidden anti-tank mines.

For the attainment of these and such other objects as may herein appear or be pointed out I have shown a number of embodiments of my invention in the accompanying drawing, wherein:

Fig. 1 is an electrical diagram illustrating one type of device having an A. C. relay;

Fig. 2 is an electrical diagram illustrating a second type of device differing from that of Fig. 1 in the provision of a D. C. relay;

Fig. 3 is an electrical diagram illustrating a device having a grid glow tube relay; and

2

Fig. 4 is an electrical diagram of a circuit similar to that of Fig. 3, but including a condenser and inductance coil for tuning.

The explosive device of the character indicated above must be simple, compact, inexpensive, fool-proof, and certain of action. If incorporating batteries the drain must be so small as to permit a continued life of several months. I have found that these conditions are met by the use of a simple pickup loop or antenna, such as designated 10 in Fig. 1 in circuit with an A. C. relay 11. The armature 12 of the relay is in a second circuit which includes a dry cell or battery 13 and the coil 14 of the primer or firing mechanism of the explosive device 10'. A. C. relays are generally less sensitive than D. C. relays; an arrangement employing a D. C. relay is shown in Fig. 2, wherein the relay 21 is in circuit with loop 20 and a rectifier 25, which is preferably of the dry type such as a selenium or copper oxide rectifier. The armature 22 of the D. C. relay is in circuit with battery 23 and the coil 24 of the primer or firing mechanism of the device 20'. In both the circuit of Fig. 1 containing an A. C. relay and the circuit of Fig. 2 containing a D. C. relay, the loop picks up the electromagnetic field of the detector, the loop current energizing the relay to close the circuit to the primer.

In Fig. 3 is shown a circuit embodying a grid glow tube 39 of the gas filled type, the circuit of grid 31 being inductively coupled with loop 30 and battery or dry cells 32; the plate 33 of the tube is in circuit with coil 34 of the firing or primer mechanism of the device 30' and a second battery 35. The filament 36 is connected at the juncture of the grid and the plate circuits, as shown in the figure. To increase the sensitivity of the device a coupling or step-up transformer 40 may be interposed between the loop 30 and the grid 31 of the tube 39. Inasmuch as the drain on the batteries must be small so as to permit a continued life of several months, vacuum tubes having heated filaments could not be used. The grid glow tube, however, is a cold cathode tube in which there is no battery drain until the tube is "triggered" by change in grid voltage. The batteries provide proper plate and grid potential until such time as the potential of the grid is changed as by the induction of a feeble voltage in the loop circuit caused by the electromagnetic waves of a detector. Thereat the change in grid potential triggers the tube to cause a flow of current in the plate circuit and through the coil 34 of the primer to explode the device and/or the anti-tank mine with which it is associated.

Whereas a thermionic tube having a grid central is shown in the drawings it is clear that other gas-filled tubes having either a controlled grid or controlled electrodes and using a cold cathode, may be employed. One example of the controlled electrode type of tube is the "double gap" Western Electric tube (313C). To provide a safeguard against premature firing due to malfunction while being placed in service, a time delay switch 41 may be placed in the plate circuit. The time delay mechanism may involve the use of a mechanical or electrical clockwork, or may be based on chemical, pneumatic or other action, effective to delay the closing of the circuit for several minutes or hours after removing an arming pull pin or other inaugurating means (not shown).

Fig. 4 is similar to Fig. 3 except that a condenser 38 and an inductance coil 37 are included in the loop circuit so as to tune or adjust the circuit to be in resonance with any predetermined frequency or band of frequencies of the electromagnetic detector.

I claim:

1. A device of the character described comprising, in combination, an explosive device for deterring the exploring of hidden mines by electromagnetic detectors, adapted to be placed in hidden association with the said mines, an antenna in which a voltage is induced by the electromagnetic field of an approaching detector, a self-con-

tained source of current, a cold cathode grid glow tube having its grid in circuit with the said antenna and source of current, a second self-contained source of current, and a primer mechanism the coil of which is in circuit with the said second source of current and the cathode of said controlled glow tube.

2. The combination according to claim 1 in which the first said circuit is further provided with an inductive coil and a condenser for tuning the said circuit to a predetermined frequency.
